METHOD OF CONSTRUCTING BRUSHES

Filed Jan. 3, 1922

Inventor:

Wm Unger.

By Hiram B. Swartz, Atg.

UNITED STATES PATENT OFFICE.

WILLIAM UNGER, OF WOOSTER, OHIO.

METHOD OF CONSTRUCTING BRUSHES.

Application filed January 3, 1922. Serial No. 526,800.

To all whom it may concern:

Be it known that I, WILLIAM UNGER, a citizen of the United States, residing at Wooster, in the county of Wayne and State 5 of Ohio, have invented a new and useful Method of Constructing Brushes, of which the following is a specification.

My invention relates to improvements in brushes, and particularly to improvements 10 in method of construction. Its principal object is to provide a novel method of constructing brushes of all kinds for painting, calcimining, and other kindred uses, by the elimination of head bands or ferrules, and 15 nails or other fastening means heretofore employed in their construction, for fastening bristles in the brush block or head; secondly, to simplify and cheapen manufacture, and make the bristles more compact 20 within the block and the brush more durable.

My improved method is particularly described in the following particulars, and stated in the appended claims.

25 My invention is illustrated by the accompanying drawings in which similar letters and figures of reference indicate like parts.

Referring thereto, Fig. 1 is a sectional side view of a brush showing my improved 30 method of securing the brush material within the brush block.

Fig. 2 is a view of one of the bunches of brush material, detached; Fig. 3 is perspective view of an assembled line of brush 35 material for insertion in the brush head; Fig. 4 is a horizontal cross section of Fig. 1 on the dotted line 2—2; and Fig. 5 is a vertical cross section of the brush block for a single line of brush material.

40 Fig. 4 also shows two furrows in the block, one of which is empty.

In the drawings, A is the brush block—so called, B an assembly of brush material, and C the ordinary brush handle. The 45 form of block and handle is immaterial, except the furrow or channel D therein, which is cut about three eighths of an inch deep, and of width sufficient to receive a single line of assembled brush material such 50 as shown in Fig. 3. In connection with the block A having one or more channels cut therein as aforesaid, I use the following novel method of assembling and securing

in the channels D the mass of brush material B.

A quantity of brush material such as bristles or the like, is laid out in a flat mass of sufficient thickness to snugly fill the channel D, the butt ends of the bristles or other brush material are trimmed off even- 55 ly, and in stitches of about one fourth of an inch in width, are sewed together by a strong cord d at a distance from the adjacent ends of the bristles b of about one fourth of an inch, so as to bring the line 60 of the cord stitches just below the top of the channel D, when the brush is completed.

After sewing, the body of the brush has the appearance of an assembly of bunches 65 of brush material, as shown singly in Fig. 2, the cord d being drawn tightly around each bunch from opposite sides, as there- 70 in shown.

Thus assembled, the sewed together 75 bunches b lie closely against each other in a continuous row, as shown in Fig. 3. The length of the stitch of the sewing cord may be varied to suit the needs of the material used in the brush. After sewing, the several knots of brush material comprise 80 a single linear row of brush material suited to the channel D wherein they are inserted. Before insertion in the channel the butt end of the row is immersed in liquid cement until well saturated therewith, the channel 85 is then filled with like cement, and the butt end inserted therein and pressed down until the cord seam is below the top of the channel, and the brush is then set aside in a kiln until thoroly dried when it is ready for immediate use.

Thus it is apparent, a brush is constructed without the use of either ferrule or nails or other fastenings heretofore employed in manufacture.

The tightly enveloping cords of the seam holding together the individual knots of brush material, and the saturation of cement in and about the several knots assembled as aforesaid, when hardened, produce a very elastic and durable brush. The thickness of the brush may be increased to any desired size by making additional channels in the brush block, and, in such case the several channels may unite at their respective ends, to give a better finish to the 100 105 110

brush, and the several parts may be modified to suit the trade and without departing from the spirit of my invention.

Having thus fully described my invention, what I claim as new and desire to secure by Letters Patent is—

1. The herein described method of constructing a brush, comprising constructing a brush-head with one or more longitudinal channels therein of suitable depth and width, assembling a mass of brush material flatwise in an even line and uniform thickness to fit the channel, sewing a strong cord seam in the line near the butt ends of the assembled brush material, saturating the butt ends of the brush material assembled with a liquid cement, and, finally, inserting and pressing the line of sewed together

butts into the channels, respectively, partly filled with a liquid cement, and then dry 20 hardening the cement.

2. The herein described method of constructing a brush, comprising the insertion and pressing into a channel of a brush head or block, of a flat line of brush material 25 sewed together with a strong cord seam across the butt ends of the line, after filling the channel with a liquid cement, and then dry hardening, substantially as set forth.

In witness whereof, I hereunto set my 30 hand.

WILLIAM UNGER.

In presence of two witnesses:

L. H. NISER,
HIRAM B. SWARTZ.
